CLOTHESPIN

Alvina E. Gorny, Chicago, Ill.

Application August 30, 1946, Serial No. 694,002

3 Claims. (Cl. 24—137)

1 This invention relates to improvements in clothes pins and has for its general object to provide a cheap, durable, efficient and very compact structure of this type which possesses appreciable advantages over all prior art devices of the same class known to me.

A specific object of the invention is to provide a resilient metal clothes pin which is equipped between its ends with a space adapted to receive a rope or a wire cable or wire from which clothes are customarily suspended, and with means spaced from said rope, cable or wire receiving means for yieldingly engaging the wearing apparel, sheets, towels and the like, to be suspended from but maintained out of contact with the said rope or other support.

A further particular object of the invention is to provide the rope, cable or wire receiving space of such shape as to engage the support sufficiently firmly to prevent the clothes pin from sliding along the same, and wherein the weight of the articles suspended from the clothes pin cooperates with the walls of said space to produce that result.

Another object of the invention is to provide a clothes pin which is engageable easily with and is equally easily disengageable from the supporting strand and from the suspended articles engaged therewith.

Suitable embodiments of the invention are illustrated in the accompanying drawings wherein:

Fig. 1 is a view in elevation showing a supporting strand, such as a rope, from which a fabric sheet, such as a towel, is suspended by means of clothes pins constructed in accordance with this invention.

Fig. 2 is a perspective view showing the two parts of the clothes pin and a rivet for joining the same preparatory to effecting assembly of the structure.

Fig. 3 is a central longitudinal sectional view of the completed clothes pin.

Fig. 4 is a cross sectional view, on an enlarged scale, taken through one of the members of the clothes pin.

Fig. 5 is a view similar of Fig. 3 showing a modified form of construction.

Fig. 6 is a view similar to Fig. 3 showing the clothes pin engaged with a fabric sheet hung over a supporting cord of any type that may be used the rope or the tube shown in Fig. 1 being omitted.

The said clothes pin is composed of two sheet metal members 1 that are exactly alike except

as to a structural detail mentioned below, and are composed of a highly resilient metal, preferably stainless steel. The width and thickness of the strips of metal, of which said members 1 are composed, are determined by two factors, the main one being the maximum load-carrying capacity desired to be obtained, and the second being the size of the completed structure, which is preferably as small as possible in order that an appreciable number thereof may be held in one hand of the user in order to speed up clothes hanging operations to the greatest possible degree.

Each member 1 includes an inverted L-shaped upper end portion which includes the flange 2 and a shank portion 3, the said shank portions being equipped with registering perforations 4 for the passage of the single rivet 5 which joins said shank portions 4 at a point spaced far enough from the flanges 3 to permit the operation of forming the respective male and female interengaged formations 6 between said rivet 5 and said flanges 2, which serve to prevent relative rotation of said members 1 about the axis of said rivet 5.

Next below the said shank portions 4, the members 1 are shaped to provide the substantially diamond-shaped space 7 of appreciable length, the greatest normal width of said space 7 being about equal to or slightly less than the diameter of the cables commonly used for clothes hanging purposes, and which is of less maximum normal width than the diameter of rope commonly used. Obviously, because this space 7 is closely proximate to the rivet 5 at its upper end, the flexing of these portions of the members 1 is resisted to a very high degree and, because the angle of divergence of the upper wall portions of said space 7 is small, the weight of the load suspended from the clothes pins, as shown in Fig. 1, will cause a high degree of frictional resistance to travel of the clothes pins along cable or wire (sometimes used) engaged in the said space 7.

The spacing of the widest portion of space 7 from the junctions of the shanks 1 with the shanks 6 is about one and one-half times the greatest width of said space 7.

The pressure exerted upon rope of diameter greater than the maximum width of said space 7 will be subjected to enough pressure by said walls of said space to flatten the same and thus prevent any travel of the clothes pins along the same.

Below the portions of the shanks of the members 1 which form the walls of the space 7, said

shanks are corrugated to form a plurality of substantially elliptical spaces 8, two of which are preferable to a greater or smaller number, as shown, and below the outermost end of which said shanks are maintained normally in strong yielding contact with each other. The terminal flanges 9 of the members 1 are divergent, as shown, and their extremities disposed sufficiently spaced apart to receive the largest diameter supporting strand, such as a rope, of substantially conventional size commonly used.

In suspending such articles as rugs, heavy draperies and the like, as shown in Fig. 1, the clothes pins are, of course, first mounted upon the supporting strand and the articles to be suspended from them are then inserted into place.

Obviously, as shown in Fig. 6, the fabric may be first disposed over the supporting strand and the clothes pins, of which a very appreciable number may be held in one hand of the user, then applied successively by engaging the shanks thereof between the thumb and first finger with index finger bearing upon the head flanges 2 and forced downwardly over the supporting strand and fabric suspended therefrom to any desired extent for engagement in the opposed hollows of any selected pair of corrugations.

In the event that the total thickness of the load suspended from the clothes pins is enough to effect an appreciable expansion of the portion of the latter between which the load is engaged, the said space 1 will be increased slightly in width, but experience has demonstrated that this expansion is unimportant because any disadvantage incident thereto is overcome by increasing the number of clothes pins used to support such a heavy load.

It will be observed that the corrugation of the shanks of the member 1 are arcuate and that opposed convex surface portions thereof are alternated with opposed concave surface portions to form the said spaces 8 and that the only point at which said convex surface portions meet is at the junctions of the lowest thereof with the flanges 9, the next inward pair of opposed convex surface portions being spaced slightly from each other, and the next inward pair thereof spaced slightly farther apart, this being important in that if the article to be engaged between said corrugated shank portions is fairly thick, two or all three of the opposed convex surface portions of said shanks will engage the same if the user of the clothes pins inserts the edge portion of said article to project, in part, into the lower end portion of the space 1.

The uppermost opposed convex surfaces of the corrugations are spaced apart normally farther than the next lower opposed convex portions and form the open mouth of the supporting strand receiving space.

The greatest pinch pressure on fabric of such thickness as may cause the corrugated portions of the shanks to become divergent is exerted at the mouth of the supporting strand receiving space, of course, because of its close proximity to the junction of said shanks or legs of the device.

The opposed convex portions of corrugations of said shanks or legs lie substantially tangential to planes extending divergently from the meeting line of same into the first-named space, the angle of divergence of said planes being decreased progressively until they become parallel or oppositely divergent, depending upon the thickness of the interposed fabric.

Thin fabrics and the supporting element over which they are hung will, of course, be engaged only between the lowest of said opposed convex wall portions, as shown in Fig. 6.

The flat head of the structure is very advantageous in that it operates to render easy the mounting of the same upon the supporting strand by pressure. The flanges 2 also render easy the disengagement of the structures from said strand.

The strips of metal of which the clothes-pin is made, are, preferably, devoid of sharp corners, as exemplified in Fig. 4.

The structure of Fig. 5 is intended for use only upon clothes lines of larger than ordinary diameter used for suspending rugs or the like which are never hung over the lines to dry, but require the full spring strength of the structure to carry the load and, therefore, must not be partially expanded in the space 1a of the structure of Fig. 5 wherein said space is substantially semi-cylindrical at top and preferably of enough smaller radius than the heavier rope used so as to engage the same firmly enough to prevent the aforesaid travel of the clothes pins along the same.

The clothes pins may also be used to suspend clothes from the lower bar of a garment hanger over the top of which a coat or blouse is hung, substantially as shown in Fig. 1.

I claim as my invention:

1. A clothes-pin composed of twin resilient sheet metal members having straight upper shank portion rigidly joined against movement relative to each other and terminating in outwardly projecting flanges and constituting a substantially inflexible T-shaped head portion terminating at its lower end in a pair of opposed shanks extending first divergently to a predetermined intersecting horizontal plane spaced from said head and convergently from said plane to a meeting point below said plane and terminating in flared flanges.

2. A structure, according to claim 1, wherein the divergent portions of the shanks next below the T-shaped head portion are of length approximately equal to about one and one-half times the maximum width of the open space bordered in part thereby.

3. A resilient sheet metal clothes-pin comprised of twin members each terminating at one end in an L-shaped formation rigidly secured to that of the other and providing a substantially T-shaped head portion of the structure, the remaining shank portions of said members divergent from their upper ends and convergent therebelow to a meeting point, the said convergent portions being equipped with corrugations next adjacent and to said meeting point, the last of said corrugations terminating in divergent flanges.
